PUMP TOP RE-FORMING MACHINE

Adolf H. Altvater, University City, Mo., assignor
to Milton L. Dodge, Newburyport, Mass.

Application May 22, 1934, Serial No. 726,920

25 Claims. (Cl. 12—51)

The present invention relates to machines which are used in the manufacture and repair of shoes to press the uppers of finished shoes.

Heretofore several different types of these machines have been used commercially to perform various kinds of pressing operations on the uppers of finished shoes. While the types of machines and the kinds of operations have varied widely, heretofore these machines have had one common characteristic, namely, an inside mold or shaping form engaged with the rear end of the shoe, the toe end of the shoe being left unsupported. Heretofore, considerable difficulty has been experienced in the use of these machines owing to the outward buckling of the unsupported camp of the shoe generally along the longitudinal center line thereof, resulting curiously in a weakening or cracking of the vamp along a line intersecting the longitudinal center line.

The present invention represents an improvement on the reforming machine disclosed in my pending application, Serial No. 699,028. As explained in said application, when a low-cut shoe is pulled from a shoe-making last, the strains to which the shoe is subjected cause irregularities in the skirtings along the straight runs of the top edge of the shoe, spread the skirtings outwardly so that the interior linings at the sides of the shoe are unduly exposed, and generally rob the shoe of the trim appearance intended by its designer and sought after during the various shoe making operations.

The re-forming machine disclosed in my said pending application is provided with inside and outside metallic shaping forms adapted to coact for pressing the skirtings along the top edge of a shoe. While these outside forms are removable, in the sense that they are not integral with their supporting arms, they are not readily removable, that is, not adapted for the rapid substitution of other forms as occasion requires.

Rapid substitution of forms is a matter of practical importance for several reasons. Metallic forms are not adapted for use on some kinds of upper materials, and consequently non-metallic forms must be used. Also, in operating upon a case lot of low-cut shoes, pumps for example, it is desirable to have more than one length of outside shaping forms to take care of variations in the lengths of the straight runs of the top edges. The matter of form length is also of importance in using the machine on low-cut shoes other than pumps or on shoes provided with throat ornaments. As will be shown hereinafter,

even the color of the shoes has a bearing on the use of different shaping forms. In view of the above, it will be seen that in operating upon low-cut shoes of different types, colors of upper materials and top edge straight run lengths, a rapid substitution or interchangeability of shaping forms to suit the particular work is commercially desirable.

As a practical matter in commercial shoe production, when the distortion of the upper caused by the last pulling operation is considerable, it sometimes happens that the straight runs along the top edge of the shoe are not positioned in the machine properly with respect to the inside mold or shaping form for the pressing operation, with the result that the outside pressing forms do not engage the portion of the upper to be pressed in the intended manner.

The principal objects of the present invention are to produce a machine by which the uppers of finished shoes may be pressed without danger of buckling the vamp of the shoe during the pressing operation, by which the portions of the upper to be pressed may be positioned in substantial conformity with the shaping contour of the inside mold or shaping form prior to the pressing operation, and in which the outside pressing forms are readily attachable and detachable to permit their rapid interchange and thus adapt the machine for use on different types of shoes, top edge straight run lengths, and colors of the upper materials.

To the accomplishment of these objects, and such others as may hereinafter appear, the various features of the present invention reside in certain devices, combinations, and arrangements of parts fully set forth hereinafter and then pointed out broadly and in detail in the appended claims, possessing advantages which will be readily apparent to those skilled in the art.

The various features of the present invention will be readily understood from an inspection of the accompanying drawings illustrating the best form of the invention at present known to the inventor, in which;

Figure 1 is a view in right side elevation of the reforming machine;

Fig. 2 is an enlarged detail view in sectional plan on the line 2—2, of Fig. 1, with a shoe in the machine and the operating handle pulled forward;

Fig. 3 is a view in sectional plan on one of the outside shaping forms;

Fig. 4 is a view in right side elevation, partially in section, of the re-forming machine with

the right hand swinging arm removed to show underlying parts;

Fig. 5 is a detail view in front elevation of the reforming machine;

5 Fig. 6 is a detail view in front elevation showing the swinging arm, the form supporting plate, and the shimming of the rocker plate;

Fig. 7 is a view in plan of the re-formed shoe; and

10 Fig. 8 is a view in front elevation of a Bakelite outside shaping form.

For the purpose of disclosure the shoe operated upon by the re-forming machine is illustrated and described as a low-cut shoe, herein shown for 15 convenience as a pump 8 (Fig. 7) the top edge 9 of which is bound with French cord and comprises a curvature 10 at the front, a curvature 11 at the rear, and straight runs 12 and 13, between the curvatures 10 and 11, on opposite sides of the 20 shoe, respectively. As is well known to those skilled in the art, the upper 14 and the lining 15 (Fig. 2) of the pump 8 are secured together by various seams, one of which comprises the top seam 16 (Fig. 2) lying close to and running along 25 the top edge 9. For convenience herein, the inner and outer surfaces of the shoe 8 lying close to and running along the straight runs 12 and 13 of the top edge 9 are each designated as "the skirting." The upper 14, at the rear of the shoe, 30 is closed by a back seam (not completely shown) exposing to view a back seam crease 17 (Fig. 7).

The pump 8 illustrated in Fig. 7, representing a low-cut shoe after it has been operated upon by the re-forming machine, shows the desirable 35 straight character of the runs 12 and 13 intended by the designer and sought to be attained throughout the various shoe-making operations. These runs 12 and 13 are distorted and are caused to gape under the strains to which they are subjected during the last pulling operation. The distortion or gaping robs the shoe of its trim appearance, rendering it unfit for window display and creating a distinct sales resistance. By subjecting the pump 8, after the last pulling operation, 45 to the action of the illustrated embodiment of the present invention, the original attractive lines of the runs 12 and 13 are restored (Fig. 7).

The re-forming machine is arranged in a manner similar to the machine disclosed in my pending 50 application referred to above, so that the skirtings of the completed shoe, subsequent to the last-pulling operation, may be presented between inside convex surfaces 18 (Fig. 2) formed on the opposite lateral sides of an inside mold 19, 55 and outside concave mold surfaces 20 formed, respectively, on outside shaping forms 21 and 22, as the shoe is presented to the inside mold with the toe of the shoe pointed downward and its sole vertical and facing the operative.

60 The inside mold 19 is identical with the inside shaping form disclosed in my pending application referred to above, and constitutes the enlarged front end of a flat vertically arranged arm 23 fixed to and extending forwardly from a head 24 65 at the rear of the machine.

The outside shaping form 21 differs from the corresponding shaping form, made of metal, disclosed in my pending application. As shown in Figs. 2, 3, and 5, the form 21 comprises a solid 70 rubber base portion 25 one face of which is provided with a facing 26 of a different material, vulcanized into the rubber or adhesively secured thereto. Embedded in the rubber base 25 are two studs 27 and 28, the heads of which extend outwardly from the rear face of the base adjacent 75

the top end and the center of said face, respectively.

The use of rubber as the base for the outside shaping form marks a distinct advantage over the use of a metallic form. The desired contour of 5 the shaping surface of a rubber form may be obtained by molding, whereas the proper shaping contour can be given to a metallic form only by machinery and otherwise finishing it after it is cast. The cheapness of rubber and the ease with 10 which it can be molded accurately make it a more desirable and economical material to use than metal.

The facing 26 with which the shaping surface 15 20 of the outside shaping form 21 is provided may be a felt facing, in which case the shoe is directly engaged during the re-forming operation (Fig. 2) by a soft surface. However, since the fibrous nature of felt renders it unsuitable for use with certain types of leather, the form 21 may be 20 given a smoother and more even operative surface by providing it with a facing 26 of grain surfaced leather. Excellent results may also be obtained by using a shaping form 21a (Fig. 8) made of Bakelite. This substance combines the desirable 25 properties of both metal and rubber, since it has an almost metallic hardness and smoothness and since, like rubber, it can be easily molded.

The outside shaping form 21 is adapted for ready attachment to and detachment from the 30 machine. To this end, the form 21 is mounted on a flat plate 29 which is detachably connected, as will be described hereinafter, to the front end of a flat, vertically arranged swinging arm 30, formed and pivotally hung at its rear end on a 35 bracket 31 carried by the head 24, in a manner identical with the corresponding arm disclosed in my pending application, referred to above. The plate 29 is provided with an upper vertical slot 32 (Fig. 1) and with a lower L-shaped slot 40 33, the short dimension of the flange of which extends vertically downward. The slots are adapted to receive, respectively, the shanks of the studs 27 and 28 on the shaping form 21. To lock the form 21 in its operating position on the plate 29, a 45 small depending keeper 34 is loosely pivoted to the plate 29 above the slot 33 so as to cover a portion thereof and hang with its bottom edge substantially in engagement with the head of the stud 28. With this construction the form 21 may be 50 removably secured to the plate 29 in operating position.

The form 21 may be quickly removed by merely swinging the keeper 34 away from the stud 28, lifting the form 21 so that the stud 28 leaves the 55 vertical part of the L-shaped slot 33, and then swinging the form outwardly, with the stud 27 as a pivot, as indicated in construction lines in Fig. 1. Another form may be readily substituted by placing its stud 27 in the slot 32, swinging the 60 form down against the front edge of the plate 29 with the stud 27 as a pivot, raising the form slightly in engagement with the plate to cause the stud 28 to enter the slot 33 and swing the keeper 34 rearwardly, and then pushing the form downward to lodge the stud 28 in the vertical part of the slot 33. With this operation both studs are 65 positioned in their respective slots, and the keeper 34 swings back under gravity over the stud 28.

To secure the plate 29 to the swinging arm 30, 70 the plate is provided with two holes 35, one of which is indicated in Fig. 2, which receive loosely, respectively, the shanks of bolts 36 and 37 (Figs. 1, 2, and 5) threaded into the arm 30. Interposed between the plate 29 and the arm 30 is a trans- 75

versely concavo-convex rocker plate 38 provided along its center line with two holes 39 which receive loosely, respectively, the shanks of the bolts 36 and 37. The convex face of the rocker plate 5 38 engages the plate 29, and heavy springs 40, coiled about the shanks of the bolts 36 and 37, respectively, and interposed between the heads thereof and the plate 29, resiliently hold the plate 29 in engagement with the rocker plate 38 along 10 its center line. As shown in Fig. 6, a shim 41 is carried by the shank of the bolt 37 and is interposed between the outside face of the arm 30 and the rocker plate 38. This shim construction, the purpose of which will be explained hereinafter, 15 causes the plate 29, and therefore the shaping form 21, to extend downwardly slightly to the right, viewing the front of the machine.

The outside shaping form 22 is constructed and is mounted in a manner similar to the shaping 20 form 21. That is, the form 22 is received by a plate 42 mounted like the plate 29 on the front end of a flat, vertically arranged swinging arm 43, like the swinging arm 30, pivotally hung at its rear end on the bracket 31. The plate 42 engages a rocker plate and is shimmed like the plate 29, so that it extends downwardly slightly to the 25 left, viewing the front of the machine. With this construction the two plates 29 and 42, and the shaping forms carried thereby, converge upwardly.

In order to move the outside shaping forms toward and from the inside mold, the arms 23, 30, and 43 (Fig. 2) receive loosely a horizontal bolt 44 connecting the yoked arms 45 of a lever 35 46 provided with an operating handle 47. The yoked arms 45 embrace the outside faces of the arms 30 and 43, and each of the arms 45, above and below the bolt 44, is provided with a stud 48 extending through the arm and provided with a 40 rounded end. The rounded end of each stud engages a wedge block 49, two of which are carried on the outside face of the arm 30 and two of which are carried on the outside face of the arm 43. To maintain the studs in any position of adjustment, each stud is provided with a locknut 50.

When no work is in the machine, the lever 46 occupies the position shown in Fig. 1. In this position the outside faces of the swinging arms 30 and 43 are forced into engagement with the 50 yoked arms 45 of the lever 46 by a spring 51 coiled about the bolt 44 and interposed between the arms 30 and 43 (Fig. 2). With this construction the outside shaping forms 21 and 22 normally clear the inside mold 19 as shown in Fig. 5, thereby 55 providing sufficient room for the application of a shoe to and its removal from the inside shaping form. When the handle 47 is pulled forwardly by the operative, the rounded ends of the studs 48 travel along the inclined surfaces of the wedge blocks 49, thereby forcing the arms 30 and 43 to swing towards each other and causing the outside shaping forms 21 and 22 to engage the work and press it against the inside shaping mold 19. It will be apparent that since the spring 51 forces 60 the wedge blocks 49 into engagement with the studs 48, a turning of the studs in either direction will vary the extent of movement of the outside shaping forms and this in turn will vary the pressure exerted by the forms against the shoe. 65 In order to lock the outside shaping forms in pressing position, the inclined surfaces of the wedge blocks 49 terminate in flat surfaces 52, as indicated in Fig. 2.

The operative shaping surfaces 18 of the inside 70 mold 19, like the corresponding surfaces on the

inside shaping form disclosed in my pending application above referred to, are convex and are of uniform curvature throughout their length to simulate approximately the vertical curvatures at the opposite sides of the last to which the 5 skirtings of the shoe are drawn during the lasting operation. Moreover, the operative shaping surfaces 18 on opposite lateral sides of the mold 19 converge vertically from the bottom thereof to the top in order to simulate approximately the longitudinal converging of the opposite sides of the shoe-making last towards the heel end thereof. That is, each operative surface 18 has a relation 10 to the median line of its mold simulating the relation between a side of the shoe-making last and 15 its median line.

As indicated in Fig. 4, the curvature 10 of the top edge of the pump extends out of the plane of the straight runs 12 and 13. In order to accommodate the inside mold 19 to this abrupt change 20 in direction of the curvature 10 and to permit the form to enter the shoe, the bottom of the mold is provided with a downwardly and rearwardly extending nose 53. This nose enters the shoe and extends under the vamp adjacent its 25 throat.

As shown in Fig. 4, the top of the inside mold 19 engages the inside of the shoe at its heel and constitutes a support from which the shoe is suspended. The nose 53 extends only a slight 30 way into the toe portion of the shoe, as shown in Fig. 4, thereby leaving the toe end of the shoe to hang freely. It has been found that when a shoe is so mounted on the mold 19 and the outside shaping forms are moved to press the skirtings 35 against the inside mold, there is sometimes a tendency for the vamp, generally along the longitudinal center line thereof, to buckle or to be crimped, resulting in its weakening or cracking. Stated in another way, the desirable appearance 40 (Fig. 7) of the straight runs 12 and 13 is achieved, but not infrequently at the expense of injury to the vamp. The appearance of the shoe is spoiled as a consequence, and the shoe may even be rendered unfit for sale. It should also be pointed out 45 that when the distortions of the shoe resulting from the last pulling operation are considerable, there is the chance that when the outside shaping forms engage the skirtings of a freely hanging shoe and move them into engagement with the 50 inside mold, the skirtings may not be properly positioned with respect to the forms and so may be permanently wrinkled as the result of pressing.

To prevent possible injury to the vamp during 55 the reforming operation and also to prevent wrinkling of the skirtings, the present invention contemplates the provision of means for holding the vamp against buckling or crimping during the application of pressure to the skirtings and 60 for positioning the shoe on the inside mold 19 so that the skirtings will be in substantial conformity with the shaping contour of the inside mold prior to the application of pressure by the outside shaping forms.

To these ends an arm 54 (Figs. 1 and 4) is pivoted at one end to the head 24 and extends forward under the arm 23 to a point near the inside mold 19. Pivoted to the free end of the arm 54 is a bent strip 55 comprising a forwardly 70 extending short arm 56 provided with depending ears 57 for attachment to the arm 54 by means of a pin, and a longer arm 58 bent downwardly and rearwardly at an acute angle to the arm 56. As shown in Figs. 4 and 5, the arm 58 is trans- 75

versely concavo-convex, corresponding to the curvature of the median portion of the shaping surface of the mold 19, and the concave face of the arm 58 is adjacent the mold 19. The free end 5 of the arm 58 is provided with a block 59 adapted to be inserted into the toe portion of the shoe, as shown in Fig. 4, and the length of the arm 58 is such that the short arm 56 clears the curvature 10 of the top edge of the shoe. Upward movement 10 of the bent strip 55 on the arm 54 is yieldingly prevented by a leaf spring 60 as indicated in Figs. 1 and 4, and a coil spring 61 connects the head 24 and the arm 54 and tends to pull the arm 54 downward. To limit the downward movement 15 of the arm 54 under the influence of the spring 61, the arm is pivotally secured to the depending wings of a U-shaped clip 62 (Figs. 1 and 4) the crosspiece 63 of which (Fig. 2) rests normally on a run 64 of the arm 23 formed by cutting away part of the rear portion thereof.

With this construction the operative positions the shoe in the machine by first inserting the block 59 into the shoe and then pulling the shoe upward against the tension of the spring 61 to cause the nose 53 of the inside mold 19 to enter the shoe. The shoe is then pulled further upward against the tension of the spring 61 and the heel end is pushed along the top of the mold 19 so as to rest upon it, as shown in Fig. 4. The length 25 of the arm 56 is such that the concave surface of the arm 58 engages the mold 19 when the shoe is thus mounted for re-forming, and by making the arm 58 of sufficient length so that the arm 56 will clear the curvature 10 of the 30 largest size shoe in the series, the construction shown provides for the proper positioning of shoes of all sizes.

The construction embodied in the arms 54, 56 and 58, the block 59, and the spring 61, has 40 several effects upon the mounted shoe. The force exerted by the spring 61 causes the arm 58 to be held against the inside mold 19 and also causes the block 59 to force the vamp, generally along the longitudinal center line thereof, against the convex face of the arm 58. In this manner the vamp is securely held taut so that it cannot buckle or crimp or pull away from the nose 53 and the arm 58 during the re-forming operation. The force exerted by the spring 61, acting 45 downwardly through the block 59, also causes the skirtings of the shoe to be drawn more or less taut over the inside shaping mold 19, and as a result, the skirtings, even when considerably distorted as the result of last pulling, are drawn toward each other substantially into engagement 50 with the shaping surfaces 18 of the inside mold.

Broadly considered, the stationary mold 19, the arm 58 and the block 59 constitute an inside shaping form which is normally maintained fully 60 extended by the spring 61 but which is contracted by the act of inserting the inside shaping form into the shoe. When the inside shaping form is within the shoe the springs 60 and 61 hold the mold 19 and the block 59 firmly against the rear 65 and toe ends of the shoe, respectively. Thus the inside shaping form is contractible by the act of inserting the inside form within the shoe to adapt the inside shaping form automatically to the particular size of shoe to be re-formed. The springs 60 and 61 also hold the arm 58 engaged 70 both with the mold 19 and with the shoe under the vamp generally along the longitudinal center line thereof.

In order to gage the position of the shoe on the 75 inside mold 19, a bracket 65 (Fig. 1) is secured

by screws to the top of the arm 23 and to the back of the inside mold with one arm of the bracket extending vertically above the mold as shown in Figs. 1, 4, and 5. This vertical arm engages the top edge 9 of the shoe in the vicinity of 5 the back seam crease 17 and thus limits the rearward position of the shoe in the machine.

It will be seen that the tautening of the shoe on the inside shaping form by the action of the springs 60 and 61 serves to hold the shoe on the 10 form in its gaged position and so prevents any accidental shift of position that might occur were the shoe merely loosely suspended from the top of the form. It will also be seen that the tautening of the shoe effected by the springs serves to 15 smooth out the back seam by pulling it against the top of the form.

In order that they may coact with the operative shaping surfaces 18 of the inside shaping form, the operative shaping surfaces 20 of the 20 outside forms 21 and 22, respectively are concave and are of a uniform curvature corresponding to the curvature of the shaping surfaces 18. Since the surfaces 18 converge vertically from the bottom of the mold 19 to its top, and since the swing- 25 arms 30 and 43 are vertically arranged, the shims 41 (Fig. 7) serve to cause the plates 29 and 42, and therefore the outside shaping forms 21 and 22, to converge upwardly in a manner corresponding to the upward convergence of the surfaces 18 on the mold 19. This is indicated in 30 Figs. 5 and 6, and by this construction the operative surfaces 20 of the outside forms 21 and 22, respectively, are substantially equally spaced from the coacting surfaces 18, respectively, when 35 the operating handle 47 is pushed rearwardly or when no work is in the machine.

Viewing Fig. 2, however, it will be seen that when the operating handle 47 is pulled forwardly to cause the outside shaping forms 21 and 22 to 40 engage the shoe mounted on the inside form, the forms 21 and 22 are not equally spaced throughout their operative surfaces from the respective coacting surfaces 18. When the operating handle is thus pulled forward, the resistance offered to 45 the movement of the forms 21 and 22 by the shoe causes the plates 29 and 42 to rock on the rocker plates 38 (Fig. 2), resulting in the divergence of the plates, and therefore of the forms 21 and 22, from the rear to the front of the machine. The amount of this divergence is limited 50 by stops 57 carried by the plates 29 and 42 and adapted to engage the swinging arms 30 and 43, respectively.

The purpose of this construction, permitting a 55 rocking and a forward divergence of the operative surfaces of the forms 21 and 22 in engagement with the work, is to subject the margins of the skirtings adjacent the top edge 9 to greater pressure than the opposite margins of the 60 skirtings. When the top edge 9 is provided with a binding such as a French cord or an imitation thereof, the rocking of the forms 21 and 22 insures that the binding will not be harmed. By 65 this arrangement the proper pressure is applied to smooth out the skirtings, re-form them into the positions in which they were molded on the shoe-making last during the lasting operation, and stiffen the straight runs 12 and 13 of the top edge so that they will stand up in their 70 natural positions in the finished shoe.

The effectiveness of the outside shaping forms 21 and 22 is increased by the heavy springs 40 which press the plates 29 and 42 against the rocker plates 38, respectively, along their cen- 75

ter lines when no work is in the machine. When the forms 21 and 22 engage the work, the rocking of the plates 29 and 42 over the rocker plates causes the springs 40 to be compressed. With 5 this construction, the skirtings of the shoe are subjected to compressed spring pressure in addition to the pressure determined by the adjustment of the studs 48 engaged with the wedge blocks 49.

10 It should be pointed out that if the skirtings of the shoe are so thick that the stops 67 engage the arms 30 and 43 during the rocking of the outside shaping forms before the operating handle 47 is fully pulled forward, the plates 29 and 42 will bodily lift away from the rocker plates 38, thereby being pivoted on the studs 67 and swung in this position to increase the compression of the springs 40.

15 The outside shaping forms 21 and 22 are illustrated and described herein as being detachably mounted on the plates 29 and 42, respectively, thereby permitting a rapid substitution of forms. This is a matter of great practical importance with respect to shoe color and style, and also 20 with respect to the material of which the shaping forms are made. The construction of the forms themselves has been hereinbefore stated. It will be seen that in working on large lots of 25 shoes, involving the use of different kinds of leather, ready substitution of outside shaping forms is highly desirable.

30 But the difference in leathers is only one factor making rapid substitution of outside forms desirable. The color of the shoes is another factor, and this is of importance when the forms have 35 a facing 26 of leather or of felt. It has been found that the dressing on the shoes tends to stick to leather and felt at times, so that in changing from a case of black shoes, for example, to a case of white shoes, there is the possibility of the black dressing on the form discoloring 40 the white shoes. The different types of leather of which shoes are made is also of importance in this connection since dressings set 45 in different types of leather with different degrees of permanence. As a consequence, it is necessary as a practical matter that there be separate forms for each color of dressing, and to a certain extent, for each type of leather.

50 As regards style, the present invention has been illustrated and described as used for re-forming a pump, but it is obvious that it is adapted to re-form other types of low-cut shoes. For example, it is adapted to re-form shoes provided with buckles or other ornaments at the throat of the vamp, and also to re-form shoes such as oxfords or bals. In the event that such types of shoes are to be re-formed, outside shaping forms considerably shorter than the forms 55 illustrated are desirable because the straight runs along the top edge of the shoe are frequently shorter than in the case of a pump, or the buckles or other ornaments must be cleared to prevent injury to them. The effect of a short shaping form can, of course, be gained by cutting away the lower portion of the shaping surface of a long form so that it clears the ornaments. The advantage gained by the speedy 60 substitution of forms permitted by the stud and slot arrangement herein disclosed is obvious when various lots of these types of shoes are being re-formed.

65 As shown in Fig. 5, the upper ends of the outside shaping forms 21 and 22 terminate a substantial distance from the center of the top of 70

the inside shaping mold 19. With this construction, the upper ends of the shaping forms 21 and 22 are spaced from the back seam crease 17 when a shoe is being re-formed, and as a result do not press that portion of the shoe upper materials which are directly supported by the counter. 5

When desired, heat may be supplied to the inside shaping form through a cartridge heating unit 68 (Fig. 4) electrically connected by wiring 69 to some suitable source of power and mounted within a chamber 70 formed in the front face of the inside shaping mold 19 and covered by a detachable cover 71. 10

Nothing herein explained is to be interpreted 15 as limiting the various features of the present invention in the scope of its application to use in connection with the particular machine or the particular mode of operation or both selected for purposes of illustration and explanation. While 20 the particulars of construction herein set forth are well suited to one mechanical form of the invention and to the use to which it is put, it is not limited to this use, nor to these details of construction, nor to the conjoint use of all its 25 features, nor is it to be understood that these particulars are essential since they may be modified within the skill of the artisan without departing from the true scope of the actual invention, characterizing features of which are set 30 forth in the following claims by the intentional use of generic terms and expressions inclusive of various modifications.

What is claimed as new, is:

1. In a re-forming machine, the combination 35 with an inside form and outside forms to press the skirtings along the top edge on opposite sides of a shoe against the shaping contour of the inside form, of means for holding the vamp of the shoe taut generally along the longitudinal center 40 line thereof during the pressing operation.

2. In a re-forming machine, the combination 45 with an inside form and outside forms to press the skirtings along the top edge on opposite sides of a shoe against the shaping contour of the inside form, of means for holding the skirtings taut in substantial engagement with the shaping contour of the inside form prior to the application of pressure by the outside forms.

3. In a re-forming machine, the combination 50 with an inside form and outside forms to press the skirtings along the top edge on opposite sides of a shoe against the shaping contour of the inside form, of means for holding the skirtings taut in substantial engagement with the shaping 55 contour of the inside form prior to the application of pressure by the outside forms and the vamp of the shoe taut generally along the longitudinal center line thereof during the pressing operation. 60

4. In a re-forming machine, coacting inside and outside shaping forms having substantially complementary surfaces for pressing against the inner and outer surfaces of the upper of a shoe to re-form the upper, the inside form being contractible to enter the shoe, means for causing the inside form when in the shoe to extend from the rear to the toe ends thereof, and means for causing a relative movement between the inside and outside forms with respect to their complementary 70 surfaces to effect the reforming pressure. 65

5. In a re-forming machine, coacting inside and outside shaping forms having surfaces for contacting with the inner and outer surfaces of the upper of a shoe, said inside form being 75

- justable lengthwise in accordance with the length of a shoe placed thereover, and means for relatively moving said forms to press said upper therebetween.
5. 6. In a re-forming machine, coacting inside and outside shaping forms having substantially complementary surfaces for contacting with the inner and outer surfaces of the upper of a shoe, the inside shaping form being contractible to 10 enter the shoe and being provided with means for causing it to extend within the shoe from the rear to the toe ends thereof automatically irrespective of the size of the shoe.
7. In a re-forming machine, coacting inside and outside shaping forms having substantially complementary surfaces for contacting with the inner and outer surfaces of the upper of a shoe, the inside form comprising elements adapted to 15 engage the rear and toe ends, respectively, of the shoe, and means for urging said elements apart so that the distance between their opposite ends is normally greater than the distance between the rear and toe ends of the shoe, said inside form being contractible against the influence of 20 the urging means by the act of inserting the inside form within the shoe and in its condition of insertion and contraction engaging the rear and toe ends, respectively, of the shoe.
8. In a re-forming machine, coacting inside and outside shaping forms having substantially complementary surfaces for pressing the inner and outer surfaces of the upper of a shoe to reform the upper, the inside shaping form having a 25 part engaged with the rear end of the shoe, a part engaged with the toe end of the shoe, and a part engaged with the shoe under the vamp generally along the longitudinal center line thereof, and means for causing a relative movement between the inside and outside forms with 30 respect to their complementary surfaces to effect the re-forming pressure.
9. In a re-forming machine, coacting inside and outside shaping forms having substantially complementary surfaces for contacting with the inner and outer surfaces of the upper of a shoe, the inside shaping form having a part engaged 35 with the rear end of the shoe, a part engaged with the toe end of the shoe, and a part engaged with the shoe under the vamp generally along the longitudinal center line thereof, an extension of 40 said last named part being engaged with the first named part.
10. In a re-forming machine, coacting inside and outside shaping forms having substantially 45 complementary surfaces for contacting with the inner and outer surfaces of the upper of a shoe, the inside shaping form comprising a stationary mold engaged with the rear end of the shoe, a block engaged with the toe end of the shoe, and a supporting arm for the block engageable with 50 the stationary mold, said arm being supported outside the shoe.
11. In a re-forming machine, coacting inside and outside shaping forms having substantially 55 complementary surfaces for contacting with the inner and outer surfaces of the upper of a shoe, the inside shaping form comprising a stationary mold engaged with the rear end of the shoe, a block engaged with the toe end of the shoe, and a supporting arm for the block engaged with the stationary mold, said arm being supported outside the shoe, and means connected to the arm 60 outside the shoe tending to engage the arm both with the stationary mold and with the vamp of the shoe generally along the longitudinal center 65
- line thereof and to separate the mold and the block.
12. In a re-forming machine, the combination with an inside shaping form and an outside shaping form to press the skirting along at least one straight run of the top edge of a shoe against the shaping contour of the inside form, of means for holding the said skirting run taut in substantial engagement with the shaping contour of the inside form prior to the application of pressure 10 by the outside form. 5
13. In a re-forming machine, the combination with an inside shaping form and outside shaping forms to press the skirtings along the top edge on opposite sides of a shoe against the shaping 15 contour of the inside form, of means for holding said skirtings taut in substantial engagement with the shaping contour of the inside form prior to the application of pressure by the outside forms. 20
14. In a re-forming machine, the combination with an inside shaping form accessible to the operative for placing a shoe thereon, and outside shaping forms movable toward and from the inside form at opposite sides thereof to press the 25 skirtings along the top edge of a shoe against the shaping contour of the inside form, of means for preventing a shift of position of the shoe on the inside form during the movement of the outside forms. 30
15. In a re-forming machine, the combination with an inside shaping form accessible to the operative for placing a shoe thereon, and outside shaping forms movable toward and from the inside form at opposite sides thereof to press the 35 skirtings along the straight runs, respectively, of the top edge of the shoe into conformity to the shaping contours of the opposite sides, respectively, of the inside shaping form, of means including rocker members permitting the outside 40 forms to rock during their movement about axes parallel to the longitudinal center line of the inside form. 35
16. In a re-forming machine, the combination with a head, an inside shaping mold fixed to said 45 head and accessible to the operative for placing a shoe thereon, an arm on each side of the inside mold pivoted to the head, and a pair of outside shaping forms to press the skirtings along the top edge of the shoe against the shaping contour of the inside mold, of means for mounting the outside forms on the arms, respectively, including a rocker member secured to each arm and a form support resiliently secured to the arm in engagement with the rocker member. 50
17. In a re-forming machine, the combination with a head, an inside shaping mold fixed to said head and accessible to the operative for placing a shoe thereon, an arm on each side of the inside mold pivoted to the head, and a pair of outside 55 shaping forms to press the skirtings along the top edge of the shoe against the shaping contour of the inside mold, of means for removably connecting the outside forms to the arms, respectively, including a form support, provided with slots, secured to each arm and studs carried by the forms for insertion in the slots. 60
18. A re-forming machine having, in combination, a head, an inside mold fixed to said head and accessible to the operative for placing a shoe 70 thereon, an arm pivoted to the head, an outside shaping form to press the skirting along at least one straight run of the top edge of the shoe against the shaping contour of the inside mold, means for removably connecting the outside form 75

to the arm, including a slotted member carried by the arm and studs carried by the form for insertion in the slots, and a keeper maintaining the studs in the slots.

5 19. In a re-forming machine, coacting pressing molds having substantially complementary shaping surfaces for pressing the inner and outer surfaces of the skirting along at least one straight run of the top edge of a shoe to re-form the upper, at least one of said molds comprising a solid base portion a surface of which is one of the complementary shaping surfaces, and being provided with a shoe-contacting surface of a different material from the remainder of said mold.

10 20. In a re-forming machine, the combination with a head, an inside mold fixed to said head and accessible to the operative for placing a shoe thereon, an arm on each side of the inside mold pivoted to the head, a pair of outside shaping forms to press the skirtings along the top edge of the shoe against the shaping contour of the inside mold, and form supports carried by the arms, of means for removably securing the outside forms to the form supports.

15 21. In a re-forming machine, the combination with an inside form and outside forms to press the skirtings along the top edge on opposite sides of a shoe against the shaping contour of the inside form, said outside forms being movable towards and away from the inside form about axes parallel to the longitudinal center line of the inside form, of means for holding the vamp of the shoe taut generally along the longitudinal center line thereof during the pressing operation.

20 22. In a re-forming machine, the combination with an inside form and outside forms to press the skirtings along the top edge on opposite sides

of a shoe against the shaping contour of the inside form, said outside forms being movable towards and away from the inside form about axes parallel to the longitudinal center line of the inside form, of means for holding the skirtings taut in substantial engagement with the shaping contour of the inside form at least during the movement of the outside forms towards the inside form. 5

23. In a re-forming machine, the combination with an inside shaping form accessible to the operative for placing a shoe thereon, and outside shaping forms movable towards and away from the inside form to press the skirtings along the top edge on opposite sides of a shoe against the shaping contour of the inside form, said outside forms being movable about axes parallel to the longitudinal center line of the inside form, of means for preventing a shift of position of the shoe on the inside form during the movement 10 15 of the outside forms. 20

24. In a re-forming machine, the combination with a head, an arm pivoted thereto, and an outside shaping form connected yieldingly to the arm, of means permitting a rocking of said outside shaping form during its yield. 25

25. In a re-forming machine, coacting inside and outside shaping forms having substantially complementary surfaces for contacting with the inner and outer surfaces of the upper of a shoe, 30 to re-form the upper, the inside form being contractible to enter the shoe and remaining stationary therein during the re-forming operation in a position extending from the rear to the toe ends thereof, and the outside forms being movable 35 towards and away from the inside form.

ADOLF H. ALTVATER.
